[57] **CLAIM**

The ornamental design for a square for wood and metal construction work, as shown and described.

DESCRIPTION

FIG. 1 is a front elevational view of a square for wood and metal construction work showing my new design, the rear being a mirror image thereto;

FIG. 2 is a left side elevational view thereof;

FIG. 3 is a right side elevational view thereof;

FIG. 4 is a top plan view thereof;

FIG. 5 is a bottom plan view thereof.
